SCAFFOLDING CONNECTION

Alexander Howie, Shaker Heights, Ohio

Application May 8, 1948, Serial No. 25,843

5 Claims. (Cl. 304—4)

1

This invention relates, as indicated, to a scaffolding connection, but has reference also to a novel form of locking pin which is especially adapted for use in conjunction with such connection.

A primary object of the invention is to provide a scaffolding connection which is of extremely simple, yet durable and rugged construction.

Another object of the invention is to provide a scaffolding connection which consists of a minimum number of parts, which may be cut or stamped from sheet metal, and quickly and easily bent to finished form by means of simple and inexpensive bending equipment and dies.

A further object of the invention is to provide a scaffolding connection of the character described which is highly effective for connecting the ends of scaffolding members and rigidly maintaining them in connected relation.

A still further object of the invention is to provide a novel locking pin or fastening device which coacts with the scaffolding connection and scaffolding members in a novel manner to rigidly lock the parts in assembled relation.

Other objects and advantages of the invention will be apparent during the course of the following description.

In the accompanying drawings, forming a part of this specification, and in which like numerals are employed to designate like parts throughout the same,

Fig. 1 is a side elevational view of a scaffolding connection embodying the invention;

Fig. 2 is a top plan view of the scaffolding connection;

Fig. 3 is a perspective view of the scaffolding connection, and showing also the manner in which members comprising the scaffold are supported by and connected to said scaffolding connection;

Fig. 4 is a fragmentary cross-sectional view, taken on the line 4—4 of Fig. 3;

Fig. 5 is a side elevational view of one of the locking pins shown in Fig. 4;

Fig. 6 is a bottom plan view of the locking pin of Fig. 5;

Fig. 7 is a side elevational view of a plate which forms a part of the locking pin of Figs. 5 and 6;

Fig. 8 is a side elevational view of a modified form of scaffolding connection embodying the invention;

Fig. 9 is a top plan view of the scaffolding connection of Fig. 8;

Fig. 10 is a perspective view of the scaffolding connection of Figs. 7 and 8, and showing also

the manner in which members comprising the scaffold are supported by and connected to said scaffolding connection, and

Fig. 11 is a fragmentary cross-sectional view, taken on the line 11—11 of Fig. 10.

Referring more particularly to Figs. 1 to 7 of the drawings, the scaffolding connection in this embodiment of the invention comprises four vertically-extending channel-shaped members 1, so arranged in relation to each other that the webs 2 of the members form an opening 3 for the reception of the ends of wooden scaffolding beams commonly known as 4 x 4's. In Fig. 3, a 4 x 4, designated by reference numeral 4 is shown as disposed in the upper portion of the opening 3, and another 4 x 4, designated by reference numeral 5, is shown as disposed in the lower portion of the opening 3, in endwise abutment with the first 4 x 4.

Each of the members 1 is preferably formed of sheet metal, bent to provide parallel flanges 6, from which rectangular projections 7 extend, intermediate the ends of the flanges, these projections 7 being coplanar with the flanges 6.

Disposed within each of the members 1 is a member, also formed from sheet metal and having a body portion 8 forming a shelf or seat for the support of the end of a horizontal 4 x 4, as clearly shown in Fig. 3. This member is provided at its rear edge with a downwardly extending flange 9, which is spot-welded to the web 2 of the member 1, and at the sides thereof with downwardly extending flanges 10, which are spot-welded to the flanges 6 of the members 1, and to the projections or extensions 7 of the flanges 6.

For the purpose of maintaining the members 1 in the relationship shown, and in order to rigidify the structure as a whole, I have also provided vertically-extending angle members 11, the legs of which are spot-welded to the outer faces of the flanges 6 of the members 1, these angle members being coextensive in length with the flanges 6.

It will be further noted that each of the members 1 is provided adjacent the upper and lower ends of the webs 2 thereof with circular openings 12, the openings in the web of one member being in axial alignment with the corresponding openings in the web of the directly opposite member. Similarly, the projections or extensions 7 of each member are provided with axially-aligned openings 13. The function of these openings will be presently described.

For the purpose of anchoring or fastening the lower end of the beam 4 and the upper end of

the beam 5 to the scaffolding connection, special fastening devices or locking pins are employed, which are clearly shown in Figs. 3, 4, 5, 6 and 7 of the drawings. Each of these devices comprises a member 14 formed of round rod, about $\frac{3}{4}$ " in diameter, and bent sharply at one end to provide a handle 15, which extends at substantially a right angle to the member 14. The other end of the member 14 is slotted, as at 16, this slot being coplanar with the handle 15. Disposed within the slot 16 is a rectangular-shaped plate 17 having a slot 18 therein which extends diagonally across the plate. The plate 17 is permanently secured within the slot 16 by means of a pin or rivet 19, the ends of which are anchored in the member 14 and which extends across the slot 16 and through the slot 18. It may be noted, at this point, that the plate 17 may be rotated from the position shown in Fig. 5 to a position in which its longer dimension is in axial alignment with the member 14, the length of the slot 16 being sufficient for this purpose.

The lower end of the beam 4 is provided with a circular opening extending therethrough, which opening is aligned with the openings 12 in the members 1. The plate 17 of a fastening device is then turned so that its longer dimension is in axial alignment with the member 14, after which this end of the device is inserted through an opening in the beam 4 and through the opening 12 of the opposite member 1. The handle 15 serves as a stop which bears against the web 2 of the first member 1 to limit the aforesaid movement of the fastening device.

The plate 17 is then turned to an upright position, and is then struck a blow with a hammer, thereby causing the plate to move downwardly, the movement of the pin 19 in the inclined slot 18 producing a wedge-like engagement of the plate 17 with the web of the member 1. The beam 4 is thus firmly locked to the scaffolding connection by the connecting device which has been described.

In the same manner, the beam 5 and the four horizontal 4 x 4's are locked to the scaffolding connection, as clearly shown in Figs. 3 and 4.

Since the plate 17 is coplanar with the handle 15 of each locking pin, the direction of the handle serves as a means of properly orienting the plate 17 with respect to the scaffolding connection, thereby greatly facilitating assembly. In other words, during assembly, the assembler need only be sure that the handle 15 extends downwardly, thereby automatically insuring that the plate 17 is in proper position to be struck a hammer blow for the purposes stated.

Diagonal braces or members 20, in the form of 4 x 4's, may also be employed in building the scaffold, and the ends of these may be wedged between the flanges 6 and the fastening devices, as best shown in Fig. 3. Where such a diagonal brace is used at a point where a locking pin is not used, a short piece of 2 x 4 may be used as a wedge to wedge the brace in position.

It is thus seen that I have provided a scaffolding connection or the like, which is of extremely simple, yet durable and rugged construction, which consists of a minimum number of parts which may be cut or stamped from sheet metal and quickly and easily bent to finished form by means of simple and inexpensive bending equipment, and dies, and which is highly effective for connecting the ends of scaffolding members and rigidly maintaining them in connected relation.

It is also seen that I have provided a locking or

fastening device which coacts with the scaffolding connection and scaffolding members in a novel manner to rigidly lock the parts in assembled relation.

In Figs. 8 to 11 inclusive of the drawings, I have shown a modification of the scaffolding connection which is used for scaffolding consisting, in the main, of 2 x 4's, 2 x 6's, etc.

The scaffolding connection, in this modification 10 comprises a pair of vertically-extending sheet-metal channels, so arranged in relation to each other that the webs 22 and the flanges 23 of the channels form an opening 24 for the reception of the ends of 2 x 4's, the upper 2 x 4 being designated 15 in Figs. 10 and 11 by reference number 25 and the lower 2 x 4 by reference numeral 25', the 2 x 4's being in endwise abutment with each other. The flanges 23 of one of the channels are in abutment with the flanges 23 of the opposite channel, as best shown in Fig. 9.

For the purpose of maintaining the channels 22-23 in the relationship shown, and in order to rigidify the structure as a whole, I also provide channel-shaped members formed of sheet metal, bent to provide webs 26 which are spot-welded to the outer faces of the flanges 23, and parallel flanges 27 which are coplanar with the webs 22 of the channels 22-23, and from which rectangular projections 28 extend, intermediate the ends of the flanges 27, these projections 28 being coplanar with the flanges 27.

I further provide similar channel-shaped members formed of sheet metal, bent to provide webs 29 which are spot-welded to the outer faces of the webs 22, intermediate the vertical edges of such webs, and parallel flanges 30 which are disposed at right angles to the webs 22 of the channels 22-23, and from which rectangular projections 31 extend, intermediate the ends of the flanges 30, these projections 31 being coplanar with the flanges 30.

Disposed within each of the channels 26-27 is a member, also formed from sheet metal and having a body portion 32 forming a seat or shelf for the support of the end of a horizontal 2 x 4, 45 as clearly shown in Fig. 10. The member 32 is provided at its rear edge with a downwardly-extending flange 33, which is spot-welded to the web 26 of the channel 26-27, and at the sides thereof 50 with downwardly-extending flanges 34, which are spot-welded to the flanges 27 and projections 28 thereof.

Disposed within each of the channels 29-30 is a member, formed from sheet metal and having a body portion 35 forming a seat or shelf for the support of the end of a horizontal 2 x 4, 55 as clearly shown in Fig. 10. The member 35 is provided at its rear edge with a downwardly extending flange 36 which is spot-welded to the web 29 of the channel 29-30, and at the sides thereof 60 with downwardly-extending flanges 37, which are spot-welded to the flanges 30 and projections 31 thereof.

It will be further noted that each of the channels 22-23 is provided adjacent the upper and lower ends of the webs 22 thereof with circular openings 38, the openings in the web of one channel being in axial alignment with the corresponding opening in the web of the directly opposite channel. The webs 29 of the channels 29-30 are also provided with circular openings 39 in registration with the openings 38. Similarly, the projections or extensions of each of the channels 22-23 and 26-27 are provided with 70 axially-aligned openings 40. The openings 38, 39

and 40 are for the reception of connecting devices shown in Figs. 5, 6 and 7, so that no further description of the methods of connecting the 2 x 4's to the scaffolding connection is believed to be necessary.

While the construction of the scaffolding connection shown in Figs. 8 to 11 inclusive, is somewhat different than that shown in Figs. 1 to 7 inclusive, it is apparent that it has the same advantages and merits as the latter, and is used in virtually the same manner. The modified form of scaffolding connection is also adapted, with necessary changes in dimensions, to use with 2 x 6's and other standard types of beams or lumber.

It is to be understood that the forms of my invention, herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

1. A scaffolding connection or the like, comprising channel-shaped sheet metal members arranged with their webs defining a vertical opening therethrough of rectangular cross-section, the flanges of said channels extending outwardly and away from said opening, and members for seats for scaffolding members, said seat members disposed between the flanges of said channels and extending at right angles to the flanges of said channels.

2. A scaffolding connection, as defined in claim 1, in which the flanges of said channels are provided intermediate their ends with extensions of

rectangular form which are coplanar with said flanges, and said seat members are also disposed between said extensions.

3. A scaffolding connection, as defined in claim 2, in which said channels are maintained in said arrangement by means of sheet metal angles which are welded to the outer faces of the flanges of the channels.

4. A scaffolding connection, as defined in claim 10 3, in which said channels are provided with circular openings adjacent the upper and lower ends of the webs thereof.

5. A scaffolding connection, as defined in claim 15 4, in which said extensions are provided with circular openings.

ALEXANDER HOWIE.
